UNITED STATES PATENT OFFICE.

ADELMER M. BATES, OF CLEVELAND, OHIO, ASSIGNOR TO BATES VALVE BAG COMPANY, OF CLEVELAND, OHIO, A CORPORATION OF WEST VIRGINIA.

MACHINE FOR FILLING VALVE-BAGS.

980,906.

Specification of Letters Patent. Patented Jan. 10, 1911.

Application filed February 23, 1907. Serial No. 358,835.

To all whom it may concern:

Be it known that I, ADELMER M. BATES, a citizen of the United States, residing at Cleveland, in the county of Cuyahoga and 5 State of Ohio, have invented a certain new and useful Improvement in Machines for Filling Valve-Bags, of which the following is a specification.

My invention relates to machines for filling bags with measured amounts of material by weight and has for its object to provide new and improved constructions in machines of that class.

The invention relates more particularly 15 to machines for filling valve bags or other receptacles which have to be filled through a relatively small opening, and contemplates an arrangement for suspending the bags upon filling tubes, which tubes, together with the bags, are connected with scales to measure the proper amount of material which the bags are to receive, the tubes and their associated parts being automatically disengaged from a stationary 25 part of the machine by operation of the scale.

By making the parts of the apparatus immediately connected with the bags capable of easy disengagement from the rest of 30 the machine I obtain a degree of accuracy in the measurement of the material which is not possible in the older forms of bag filling machinery.

My invention also contemplates supporting the bag from the top alone instead of giving it the ordinary support at the bottom, although the bags might be so supported and jiggled if necessary if the character of the material of which the bags are 40 made or of the material with which they are to be filled should make such a support expedient.

The invention has for its object also such further improvements and novel devices as are shown and will be described in the following specification.

The invention is illustrated in the accompanying drawings, wherein—

Figure 1 is a front elevation of a portion 50 of the machine; Fig. 2, a side elevation with parts in section; Fig. 3, a side elevation with the parts in a different position; Fig. 4, a section on line A—A, Fig. 2, and

Fig. 5, a section on line B—B, Fig. 2. Fig. 6, a side diagrammatic view of the jiggling apparatus.

Like letters of reference indicate like parts in all the drawings.

It will be understood that the machine will ordinarily be constructed to fill a number of bags at the same time. It will only be necessary, however, to show the devices for filling a single bag.

1 is a hopper or bin containing the material with which the bags are to be filled, this hopper terminating preferably in a cylindrical feeding chamber 2 in which revolves a shaft 3 carrying the preferably curved propeller blades 4, 4. The discharge opening 5 in the feed chamber is controlled by a valve 6.

It may be said that any form of feeding device may be used as this forms by itself no part of my present invention.

The bag is supported at the top by a filling tube 7, which extends through its filling opening, and preferably on the sides and back by the cradle 8. The filling tube normally aligns with discharge opening 5, being held against a block 9 on the outside of the filling chamber by the operation of the scale which will be described later. The filling tube is connected with a swinging frame work consisting of two uprights 10, 10 connected by the preferably integral cross pieces 11, 12, and 13, the inner end of the filling tube being secured to a bracket 14 extending from the cross piece 13. The cradle is supported by the bracket 15. The uprights 10 are riveted to the sides of the cradle. This frame work carrying the filling tube and the cradle is connected with the rest of the machine so as to be capable of some vertical movement. It is also associated with some form of weighing apparatus so that the filling tube will be held in alignment with the discharge opening of the filling chamber during the filling operation and will be free to move away from the same when the required quantity of material has been inserted in the bag.

For example, in the machine illustrated in the drawings, I provide the ends of the uprights 10 with forks 16 which rest upon the knife edges 17 on the scale beams 18 suitably connected together to form a rigid frame work and balanced by

the weight 19. The upper end of the frame work carrying the filling tube is guided in any suitable manner. For example, I provide a cross rod 20 preferably made in two sections connected by the turn buckle 21, one end of the cross rod being apertured and having the knife edge 22 in the aperture bearing upon a pin 23 on a bracket 24 connected with the stationary part of the machine, the other end of the cross rod having a similar aperture through which extends pin 25 on the cross piece 11 of the frame work. It will be seen that the filling tube is perfectly free to and will move away from the discharge opening in the filling chamber as soon as the gravity of the weight 19 is overcome by the insertion of the proper amount of material into the bag. This arrangement insures a very high degree of accuracy of measurement. I also provide automatically operated means for shutting down valve 6 simultaneously with the disengagement of the filling tube. In the machine shown in the drawings the valve closing mechanism is operated directly through the movement of the vertically movable frame.

26 is a bell crank pivoted by a shaft 27 having bearings in the bracket 24. A coil spring 28 is wrapped around shaft 27 with a loop 29 bearing against the lower arm of the bell crank. The bell crank is provided with the handle 30. The upper end of the bell crank normally engages with a dog 31 pivoted by a pin 32 in the bifurcated end of a weight 33, the same shaft 32 serving to pivot the weight to a yoke 24 extending from a stationary part of the machine. The lugs 35, 35 at the end of the weight have slots 36, 36 which receive the ends of a pin 37 carried by the dog. These slots are preferably considerably larger than the diameter of the pin. At the other end of the weight is a spring piece 38 which normally rests upon the cross piece 12 of the vertical frame work. The valve 6 which extends through a slot in block 9 is attached to the lower end of the bell crank by a fork 39 in which are slots 40, making a loose connection with the pins 41 on opposite sides of the bell crank. The parts are shown in these positions in Figs. 1 and 2. A downward movement of the frame caused by the tilting of the scale beam operates to bring the parts in the positions shown in Fig. 3; that is, cross piece 12 will move out from under the spring piece 38, the weight will tilt on its pivot, striking a sharp blow on the pin 37 of the dog, causing the dog to release the bell crank which is turned on its pivot by coil spring 28, forcing the valve downward across the discharge opening and shutting off the feed. The weight delivers a hammer like blow upon the dog because of the loose connection made by pin 37 in slots 36 and the bell crank operates in

the same way upon the valve, thus overcoming the tendency of the parts to stick. A stop 42 is provided for the weight. The frame and filling tube may be returned to their normal positions by lifting up the handle 30. The weight is provided with a pivoted loop 43 which comes into engagement with a groove 44 on the handle, the weight being thus lifted into its initial position.

The scale beams 18 have the grooved blocks 45 supported on the knife edges 46. The weight 19 is hung from a threaded bolt 47 and held in adjustment by nuts 48, 48. It will be observed that the machine is so constructed that the bearing parts are positioned and covered so as not to be clogged by any loose material that may come from the machine.

It is important that the vertically movable frame should be held from lateral motion and the filling tubes accurately guided into position in alignment with the discharge opening of the feed chamber. This I accomplish by means of the double scale beam with its engagement with the cradle on each side. This engagement must be necessarily a sliding one, that is, there must be a sliding connection between the knife edges 17 and the sides of the cradle. In order to reduce friction, I prefer to cut away the inner side of the knife edge as shown in Fig. 5, thus forming a point 49 in contact with the side of the cradle. The knife edges 46 may be constructed in the same manner.

In the mouth of the feed hopper is preferably an agitator consisting of a shaft 50 on which are propeller blades 51. The shafts 3 and 50 may be driven either independently or one from another. The bag 105 may be held upon the filling tube 7 in any desired manner, for example, I have shown a clip 52 pivoted to the parts 14 which is pressed against the material of the bag by a cam 53 pivoted in a fork 54 on the diagonal brace 14 and provided with a handle 55.

I wish it to be understood that I do not desire to be limited to the exact details of construction shown and described for obvious modifications will occur to any person skilled in the art.

The jiggling device, which may or may not be used, but when used serves on occasion to jig or shake the bag, is set out in Fig. 6, wherein 56 is the jiggling board and having 120 the downwardly depending jiggling bar 57 in the sleeve 58, which is mounted on the rock lever 59 fulcrumed on the standard 60. The outer end of this lever has the link 61 on the treadle 62, which is fulcrumed at 63. 125 Associated with the lower end of the sleeve 58 is the eccentric shaft 64, driven by the belt 65 and carrying the eccentric 66 adapted to operate against the lower end of the bar 57 to oscillate the parts. The opera- 127

tion of the treadle tilts the lever 59 and raises the jiggling device so as to bring it into operative relation to the bag above. This may be done at any part of the tilting 5 of the bag where such action is desired. It will be understood that this structure is purely diagrammatic, the supporting frame and parts not being shown.

The use and operation of my invention 10 are as follows: Referring to the jiggling apparatus, it is enough to say that it is arranged so as to be, at the will of the operator, in or out of action. In many cases it will not be necessary to jig the bag or shake 15 it, as the pressure of the material supplied through the filling tube will be sufficient to thoroughly fill the bag. The bag is shown as without a bottom support except when the jiggling table is brought into operative 20 relation with it. We have, therefore, here illustrated a discontinuous top support for the bag for when it is on the jiggling table it is not supported on the tube, a discontinuous bottom support for a similar reason, 25 and a discontinuous jiggling action. When no jiggling is done the bag is supported wholly from the top and from within. Looking at the filling tube, we find that it is a separable filling tube, that it is a movable 30 tube in the sense that it moves with relation to the part from which it is supplied. It is capable, therefore, of disassociation with reference to the feeding apparatus. The entire bag support, when the bag is supported 35 on the tube, is in permanent relation with the scale and the filling tube is also, so to speak, rigid on the scale, or so as to move with its arm. The cut-off is tangential to the circle of the rotating feed part, which 40 brings its inner face close to such circle and therefore prevents the packing of the material in the passage-way leading to the filling tube. The cut-off, by the mechanism described, is moved by a hammer blow to start 45 it even though the material shall have packed about it. This hammer blow is effected by means of the mechanism consisting of weights, dogs and enlarged pivot slots, as illustrated. In the entire scale device it 50 will be observed that the knife edge is uppermost to keep the machinery clean and that the weight side of the scale lever is one-half as long as the other. The whole drawing, particularly the jiggling device, is to be 55 taken as more or less diagrammatic.

The apparatus in the position shown in Fig. 2' is ready for action. When the machine is to be filled, for example by sugar, there will be a supply in the upper hopper 60 and the agitating device on the shaft 50 will keep it stirred and feed it down into the feeding device, which consists of a cylindrical case and a double armed rotary feeder. The cut-off is refracted so that the passage 65 is open through the same into the filling

tube. On this filling tube the bag is held in position by the bag clamp and the bag is supported on the tube from within. The process of filling the bag will continue until it has reached the amount balanced by the weight 19 when a slight increase in weight 70 will start the bag support and its associated mechanism down. The moment it starts down, however, the support is taken away from the weight 33 and the latter drops 75 throwing the dog 31 out of engagement with the elbow crank lever 26. The dog is released by a hammer blow because of the movement of the pin in the slot. The spring throws the elbow crank lever around, driving the cut-off downward into closed position. It is started by a hammer blow because of the relation of the slot 40 and pin 41. Here the parts will be in the position indicated in Fig. 3. The flow will be cut off 80 and the bag will be filled and be supported by the scale alone. As previously suggested, if during any portion of this action it is necessary to jig the bag it may be done by operating the treadle so as to force the jiggling board up against the bottom of the bag, 85 whereupon the bag is supported on the jiggling board and is jiggled thereby to shake down its contents. When the bag is discharged from its support on the scale, the 90 scale portions will rise and the filling tube will resume its relation opposite the opening in the feeding device. The operator now seizes handle 30 and raises it until all the parts assume the position indicated in Fig. 95 100 2. The stop 42 serves as a stop for the several parts as indicated in Figs. 2 and 3. Before this is done, however, a new bag will have been put on the filling tube. The weight on the scale beam is adjustable and 105 the jig board is adjustable.

This device is, of course, applicable so far as some of its essential features are concerned, to the filling of a form of package other than a bag, the essential point being that the bag or other package or receptacle is mounted on the scale beam along with the filling tube. Where a soft flexible bag is used, and also in other cases, the bag may be held on the tube, but that is a mere incident in a convenient adaptation of the device to the filling of bags. As previously stated, the essential feature, broadly speaking, as applied to any package is that the package and the filling tube should be mounted on the scale beam so as to move therewith, and as applied to the filling of bags an important detail of the structure is that the bag itself 115 be hung upon or supported by the tube.

I claim:

1. The combination of a scale, a feeding device for feeding the loose granular material, and a valve package filling and holding tube extending horizontally to hold the package and feed the material thereto and 120 125 130

- separately mounted on a movable part of the scale.
2. The combination of a scale, a feeding device for feeding the loose granular material, and a valve package filling and holding tube extending horizontally to hold the package and feed the material thereinto and separately mounted on a movable part of the scale, and a cut-off between the feeding device and filling tube.
3. The combination of a scale, a feeding device for feeding the loose granular material, and a valve package filling and holding tube extending horizontally to hold the package and feed the material thereinto and separately mounted on a movable part of the scale, and a cut-off between the feeding device and filling tube, the feeding device having a rotating part and the cut-off being tangential to the path of rotation of the feeding device.
4. The combination of a feeding device having a rotary feeder, with a filling tube laterally projecting therefrom, and a cut-off between them tangential to the path of the rotating device.
5. In a package filling machine, the combination of a feeder and a scale, with a horizontally disposed filling tube mounted on the scale, the filling tube held in operative relation to the feeding device by the weight of the scale.
6. In a package filling machine, the combination of a feeding device with a horizontally disposed laterally projecting combined filling tube and package holder separately mounted.
7. In a package filling machine, the combination of a feeding device with a horizontally disposed laterally projecting combined filling tube and package holder separately mounted and a separate package engaging cradle.
8. In a package filling device, the combination of a feeding device relatively fixed in position, with a combined package holding and filling tube movable with the package out of alignment with the feeding device.
9. In a package filling device the combination with a feeding device relatively fixed in position of a package holding and filling tube and means responsive to the weight of the contents of the package for moving said tube with the package out of alignment with the feeding device.
10. In a package filling device the combination of a feeding device with a horizontally disposed package filling tube adapted to enter the package and serve as the support therefor from within the package.
11. In a package filling device the combination of a feeding device with a horizontally disposed package filling tube adapted to enter the package and serve as the support therefor from within the pack-
- age, and a clasp outside the package in opposition to the tube to clamp the package material between them.
12. In a package filling device the combination of a feeding device with a horizontally disposed package filling tube adapted to enter the package and serve as the support therefor from within the package, and a scale on a movable part of which the filling tube is mounted.
13. In a package filling device the combination of a feeding device with a horizontally disposed package filling tube adapted to enter the package and serve as the support therefor from within the package, and a clasp outside the package in opposition to the tube to clamp the package material between them, and a scale on a movable part of which the filling tube is mounted.
14. In a package filling device a tube approximately as long as the width of the package and adapted to be inserted through a side opening in the package and to serve as the sole support for the package by engagement with the inner walls thereof.
15. In a package filling device a tube approximately as long as the width of the package and adapted to be inserted through a side opening in the package and to serve as the sole support for the package, by engagement with the inner walls thereof and a cradle about the sides of the package to steady it.
16. In a package filling device the combination of a scale with a laterally projecting filling tube mounted on a movable part thereof and adapted to support the package from within.
17. In a package filling device the combination of a scale with a laterally projecting filling tube mounted on a movable part thereof and adapted to support the package from within, and a feeding device to and from which the filling tube is moved by the scale.
18. In a package filling machine the combination of a scale with a package supporting and filling horizontally disposed tube mounted thereon and movable therewith.
19. In a package filling machine, a scale with a movable part and means for supporting the package containing a horizontally disposed tube which enters the package on such movable part with a package feeding device separately mounted, and a cut-off and means for operating the same responsive to the movement of such movable part.
20. In a package filling machine, a scale with a movable part and means for supporting the package on such movable part, with a package feeding device separately mounted, and a cut-off and operating mechanism therefor containing means for striking a sudden blow on the cut-off responsive to the movement of such moving part.

21. In a package filling machine, the combination of a scale having a movable part with a separately mounted feeding device, a movable cut-off associated therewith, and a horizontally disposed tube associated with the movable part of the scale, the filling tube and cut-off movable toward and from each other responsive to the movement of such movable part.
- 10 22. In a package filling machine, the combination of a feeding device, a cut-off associated with the feeding device, a filling tube associated with the package supporting device, and means whereby the cut-off and the filling tube are moved with such moving part, said filling tube being horizontally disposed.
- 15 23. In a package filling machine, the combination of a feeding device with a movable cut-off therefor associated therewith, a movable filling tube horizontally disposed, and connections whereby the motion of the filling tube imparts motion to the cut-off.
- 20 24. In a package filling machine, the combination of a feeding device with a movable cut-off therefor associated therewith, a movable filling tube horizontally disposed, and connections whereby the motion of the filling tube imparts motion to the cut-off, a scale and said filling tube mounted on a movable part of the scale.
- 25 25. In a package filling machine, the combination of a feeding device with a movable cut-off therefor associated therewith, a movable filling tube, and connections whereby the motion of the filling tube imparts motion to the cut-off, and means for delivering a blow to the cut-off intermediate the movable filling tube and cut-off.
- 30 40 26. In a package filling machine the combination of a feeding device with a movable cut-off therefor associated therewith, a movable filling tube, and connections whereby the motion of the filling tube imparts motion to the cut-off, a scale and said filling tube mounted on a movable part of the scale, and means for delivering a blow to the cut-off intermediate the movable filling tube and cut-off.
- 35 45 50 55 27. In a package filling machine the combination of a scale beam with a frame rising therefrom, a horizontally disposed filling tube mounted thereon, and a feeding device in opposition to and registering with such filling tube.
- 60 28. In a package filling machine the combination of a scale beam with a frame rising therefrom, a filling tube mounted thereon, and a feeding device in opposition to such filling tube, and a guide for the top of said frame.
- 65 29. In a package filling machine the combination of a scale beam with a frame rising therefrom, a filling tube mounted thereon, and a feeding device in opposition to such
- filling tube, and a cut-off associated with the feeding device.
- 30 70 75 80 85 90 95 100 105 110 115 120 125 130
- In a package filling machine the combination of a scale beam with a frame rising therefrom, a filling tube mounted thereon, a feeding device in opposition to such filling tube, a cut-off associated with the feeding device, and connections from the frame to the cut-off whereby the latter is moved by the motion of the former.
- In a package filling machine, the combination of a scale beam with a frame rising therefrom, a filling tube mounted thereon, a feeding device in opposition to such filling tube, a cut-off associated with the feeding device, and connections from the frame to the cut-off whereby the latter is moved by the motion of the former, said connections including a hammer blow device to operate on the cut-off.
- In a package filling device, the combination of a bifurcated scale beam, with a package support comprising a cradle in which the package is hung, and a support on which the package is mounted.
- In a package filling device, the combination of a bifurcated scale beam, with a package support comprising a cradle in which the package is hung, and a support on which the package is mounted, said package support consisting of a filling tube which enters the package and supports it from within.
- In a package filling machine, the combination of a movable scale part, with a horizontally disposed filling tube thereon to support the package from within, and an adjustable jigging board to intermittently support the package from without.
- In a receptacle filling machine, the combination of a feeder and a scale with a filling tube mounted on the scale, the filling tube held in operative relation to the feeding device by the weight of the scale and adapted to be thrown out of such operative relation when any predetermined weight has been reached.
- In a filling device, the combination with a feeding device relatively fixed in position, of a package holding device, a filling tube, and means responsive to the weight of the contents of the package for moving said tube with the package out of alignment with the feeding device.
- In a filling device, the combination of a scale beam with a frame rising therefrom, a filling tube mounted thereon, a feeding device in opposition to such filling tube, and a guide for the top of said frame.
- In a filling device, the combination of a scale beam with a frame rising therefrom, an approximately horizontally disposed filling tube mounted thereon, a feeding device in opposition to such filling tube, and a cut-off associated with the feeding device.

39. In a package filling machine, the combination of a scale beam with a frame rising therefrom, a filling tube mounted thereon, a feeding device in opposition to such filling tube, a cut-off associated with the feeding device, and connections from the frame to the cut-off whereby the latter is moved by the motion of the former.

40. In a filling machine, the combination 10 of a scale beam with a frame rising therefrom, a filling tube mounted thereon, a feeding device in opposition to such filling tube, a cut-off associated with the feeding device, and connections from the frame to the cut- 15 off whereby the latter is moved by the motion of the former, said connections including a hammer blow device to operate on the cut-off.

41. In a filling machine the combination 20 of a scale beam with a frame rising therefrom, a cradle thereon in connection with a

filling tube, a feeding device in opposition to such filling tube, a cut-off associated with the feeding device, and connections from the cut-off to the scale beam and cradle whereby 25 the cut-off is moved by the motion of the scale beam.

42. In a filling machine the combination of a scale beam with a frame rising therefrom, a cradle thereon in connection with a 30 filling tube, a feeding device in opposition to such filling tube, a cut-off associated with the feeding device, and connections from the cut-off to the scale beam and cradle whereby 35 the cut-off is moved by the motion of the scale beam, said connections including a hammer blow device to operate on the cut-off.

ADELMER M. BATES.
